CLAIM

The ornamental design for a pitch standoff connector component for a construction kit, as shown and described.

DESCRIPTION

FIG. 1 is a top perspective view of a pitch standoff connector component for a construction kit in accordance with the present invention;

FIG. 2 is a bottom perspective view of FIG. 1;

FIG. 3 is a top side view of FIG. 1;

FIG. 4 is a bottom side view of FIG. 1;

FIG. 5 is a right side view of FIG. 1;

FIG. 6 is a left side view of FIG. 1;

FIG. 7 is a front side view of FIG. 1; and,

FIG. 8 is a rear side view of FIG. 1.

The dash-dot broken lines represent the bounds of the claim and all other broken lines represent the environment in which the article resides. None of the broken lines form a part of the claimed design.

1 Claim, 4 Drawing Sheets
